DEFLECTING TOOL

William N. Oswald, Dallas, Tex., assignor to Eastman Oil Well Survey Company, Dallas, Tex., a corporation of Delaware, and Eastman Oil Well Survey Corporation, Long Beach, Calif., a corporation of California, jointly

Application July 5, 1940, Serial No. 344,046

12 Claims. (Cl. 255—1.6)

This invention relates to new and useful improvements in deflecting tools.

One object of the invention is to provide an improved deflecting tool which is adapted to be lowered into the well bore for changing the inclination or direction of the well bore and which has means for drilling a full-gage hole or bore in the desired direction.

An important object of the invention is to provide a well bore deflecting tool having an improved ball and socket arrangement for connecting the tool with the drill stem, whereby the angle of deflection of the tool relative to the stem may be readily controlled, not only in the manufacture of the socket but also after assembly thereof.

A particular object of the invention is to provide an improved deflecting tool, wherein a yieldable means is mounted above the knuckle joint or connection between the tool and bit and exerts its pressure to constantly maintain the tool in its deflected position while the same is lowered through the well bore; the arrangement of the joint being such that when bottom is reached and weight applied to the tool, said joint is relieved of the pressure of the yieldable means, whereby when the tool is rotated, any tendency of the tool to cock or swing out of its oriented position is obviated and also whereby excessive wear on the various parts is eliminated.

Still another object of the invention is to provide improved deflecting pins in the knuckle joint or connection which are utilized for the purpose of controlling the angle of deflection and also for rotatably connecting the parts; said pins being so mounted that they do not absorb any thrust or shock or support any weight during rotation of the tool, whereby the life of the tool is materially increased.

A further object of the invention is to provide a tool, of the character described, which is constructed with an unobstructed passage therethrough for permitting a free circulation of drilling fluid therethrough and which is so arranged that the various movable elements which comprise the knuckle joint are protected from the downwardly flowing fluid which is circulated through said passage under pressure.

Still another object of the invention is to provide an improved tool which is constructed of a minimum number of parts and which is arranged so that it may be quickly and easily assembled or disassembled for purposes of repair, replacement, or for other reasons.

A construction designed to carry out the in-

vention will be hereinafter described, together with other features of the invention.

The invention will be more readily understood from a reading of the following specification and by reference to the accompanying drawing, in which an example of the invention is shown, and wherein:

Figure 1 is an elevation of a deflecting tool, constructed in accordance with the invention, and showing the same lowered in a well bore,

Figure 2 is an enlarged, transverse, vertical, sectional view of the knuckle joint or connection between the tool and drill stem, said connection being illustrated in the position which it assumes during lowering of the device,

Figure 3 is a similar view, with the parts in position during rotation of the tool,

Figure 4 is a horizontal, cross-sectional view, taken on the line 4—4 of Figure 2,

Figure 5 is a transverse, vertical, sectional view, taken on the line 5—5 of Figure 2, and

Figure 6 is a detail view, illustrating a bushing on the axial pin of the ball element for controlling the angle of deflection.

In the drawing, the numeral 10 designates the usual rotatable drill pipe or stem which has an elongate coupling collar 11 threaded onto its lower end. The collar 11 is adapted to connect the lower end of the drill stem with the improved deflecting tool T, whereby said tool is suspended from the lower end of the stem and may be run downwardly into the well bore A, as said drill stem is lowered therethrough. The deflecting tool T includes a pilot bit 12 which is adapted to engage the bottom of the well bore at a predetermined inclination, as will be explained, and also includes a main cutting bit or reamer 13, which is disposed at some distance above the pilot bit. The main cutting bit or reamer includes vertical cutting blades which are offset in a horizontal plane, as is clearly shown in Figure 1. When the deflecting tool is lowered into the well bore and a rotation is imparted to the drill stem, the deflecting tool is rotated to cause the pilot bit 12 to cut through the formation at the desired angle or inclination. As the pilot bit enters the formation and moves downwardly therethrough, it will be obvious that the blades 14 of the reamer or main bit will enter the formation and will serve to bore a hole, which is substantially the same size and diameter as the diameter of the bore A. It is noted that the cutting action of the pilot bit as it enters the formation, together with the follow-up action of the main bit, is usual practice.

The deflecting tool includes the body 15 of the bit 13, which is formed with a depending, internally screw-threaded collar 16 at its lower end (Figures 2 and 3). An elongate tubular shank or pipe 17 has its upper end threaded into the collar 16, while its lower end has the pilot bit 12 secured thereto by screw threads or other means. The bore of the elongate pipe 17 communicates with the bore 16a of the bit body 15, whereby a communication between the bore of the body 15 and the outlet port 12a of the pilot bit is established. The cutting blades 14 extend radially outwardly from the exterior surface of the bit body 15 and the collar 16 and it is preferable to provide a plurality of fluid ports 18 which extend through the wall of the bit body for the purpose of conducting a fluid outwardly from the bore thereof into contact with the cutting blades.

A knuckle joint K is adapted to connect the bit body 15 with the drill stem 10 and as is clearly shown in Figure 2, this joint includes a ball element 19. The ball is preferably made integral with the lower end of a tubular shank 20 which extends upwardly therefrom and which has its upper end externally screw-threaded so as to be connected in the coupling collar 11. The base of the shank 20 is formed with an annular inclined surface 21, which surface is disposed between the ball 19 and the remainder of the shank 20.

The ball 19 is mounted within a socket element or sleeve 22, which has its lower end screw-threaded onto the upper portion of the bit body 15. The upper end of the socket element 22 is curved inwardly and is provided with an axial opening 23, through which the inclined portion 21 of the shank extends. Due to the curvature of the upper portion of the socket element 22, it will be manifest that the ball element 19 is retained within said element. For rotatably connecting the ball 19 with the socket 22, said ball is provided with a pair of diametrically opposed recesses or grooves 24 and these recesses are adapted to receive radial pins 25 which extend inwardly from the socket element 22, the outer ends of the pin being suitably secured in said socket (Figure 5). To further rotatably connect the ball and socket and also to control the amount of inclination between said socket and the shank 20, the ball 19 is provided with diametrically opposed recesses 26 and 27, such recesses being formed in the exterior surface of the ball and being clearly shown in Figures 2 and 3. As is obvious from observing these figures, the groove or recess 26 has a greater length than the groove or recess 27, whereby the bottom of the recess 26 is disposed in a horizontal plane below the bottom of the recess 27. A pin 28, which is secured in the socket element 22 is adapted to engage within the recess 26 while a similar pin 29 is adapted to be received by the recess 27. Manifestly, since the recess 26 is longer than the recess 27, the pin 28 may move downwardly a further distance than the pin 29, with the result that a rotation is imparted to the socket element, whereby said element and the bit body 15 secured thereto are inclined with respect to the vertical axis of the shank 20 and the drill stem 10 to which said shank is connected. By varying the length of the recesses 26 and 27 with relation to each other, it is possible to control the angle of deflection of the bit body 15 and also of the pilot bit 12. Thus, a greater or

less angle of deflection may be obtained by merely varying the relative length of the two recesses.

In order to relieve the pins 28 and 29 of shearing stresses, the ball 19 is provided with a depending pin 30 which extends downwardly into the bore 16a of the bit body 15. Manifestly, the diameter of this pin will control the amount of deflection of the bit body 15 with relation to the shank 20 and will reduce the transmission of shearing stress to the pins 28 and 29. By varying the external diameter of this pin, a further control of the deflection may be obtained. In some instances, it might be desirable to increase the diameter of the pin 30 by merely placing a bushing 30a, such as is shown in Figure 6 on said pin. Such bushing would increase the diameter of the pin and limit the deflection of the bit body 15. The provision of the pin makes it possible to reduce the amount of deflection after the knuckle joint has been assembled and after the recesses 26 and 27 have been formed.

For constantly urging the socket element 22 downwardly with relation to the ball 19, a bearing collar 32 surrounds the lower portion of the shank 20 and has its underside curved complementary to the curvature of the upper end of said socket element. A coiled spring 33, or other yieldable means, which also surrounds the shank 20 while its lower end engaging the bearing collar 32 has its upper end engaging lock nuts 34 which are threaded on the upper portion of the shank 20. A suitable packing ring 32a is mounted within a recess in the top of the collar, said packing being engaged by the spring and sealing off around the shank. Obviously, the spring exerts its pressure to constantly urge the bearing collar 32 downwardly into engagement with the socket element 22 and thereby force said socket element downwardly with relation to the ball 19 which is carried by the shank. Suitable ball bearings 35 are interposed between the engaging faces of the bearing collar 32 and the socket element 22. Also a suitable packing ring 36 for packing off between these faces is provided, said ring being preferably mounted within an annular groove provided within the bearing collar.

When the device is being lowered downwardly through the well bore, the parts are in the position shown in Figure 2. In this position, the coiled spring 33 is holding the bearing collar 32 in contact with the socket element 22 and said socket element is urged downwardly relative to the ball 19. In such position, the weight of the bit assembly is carried by the socket and ball and the pins 28 and 29, as well as the other pins 35, are in the lower ends of their respective recesses or grooves. Due to the fact that the recess 26 is of a greater length than the recess 27 which is disposed diametrically opposite the same, it is obvious that the bit body 15 is inclined with relation to the shank 20 and the drill stem 10. As has been pointed out, this inclination is controlled by the relative lengths of the two recesses 26 and 27. Therefore, as the device lowers into the well bore A, the bit body 15, as well as the pilot bit 12 is disposed at an angle from the vertical axis of the drill stem, these parts being suspended by means of the socket which has its curved top resting upon the upper surface of the ball. It is noted that at this time, the lower portion of the ball 19 is spaced above the upper end of the bit body 15 and this upper end of the bit body is formed with an arcuate seat 31, which generally follows the contour of the ball 19. A suitable annular packing ring 38 is mounted

within a recess formed in the seating surface and the purpose of this packing will be hereinafter described. For urging the packing 38 upwardly within its groove, a plurality of fluid ports 39 extend from the bore 16a of the bit body 15 to the bottom of the groove in which this packing is mounted, whereby fluid pressure from the bore may be directed against the lower end of said packing.

From the foregoing, it will be evident that as the tool is lowered downwardly through the well bore A, the coiled spring 33 maintains the bit body 15, connecting pipe 17 and pilot bit 12 in a deflected position, as shown in Figures 1 and 2. As explained, the bit assembly is suspended from the ball element 19 by means of the socket and ball and pins 25, 28 and 29. When the bottom of the well bore is reached, the pilot bit 12 strikes said bottom as is shown in Figure 1. When the bit 12 strikes the bottom of the bore, further downward movement of the bit 12 and the parts connected thereto, which includes the bit body 15, is prevented. Since the socket element 22 is threaded onto the bit body 15, any downward movement of said socket element is also prevented. The weight of the drill stem 10 will cause a continued downward movement of the shank 20 and the ball element 19 until said ball engages the arcuate seat 37 which is formed at the upper end of the bit body 15. Such downward movement of the ball 19 to a seated position causes the pins 28 and 29, as well as the pins 25, to move upwardly within their respective recesses or grooves, as is clearly shown in Figure 3. The downward movement of the ball element within the socket 22 will of course result in a slight compression of the spring 33, whereby the force or pressure of this spring is taken off of the pins 28, 29 and 25. The weight of the drill stem is then carried by the surface of the ball 19 engaging the seat 37. Since the ball and socket connection is relieved of the spring, a rotation of the bits will not result in a tendency of the bits to be swung or urged from the oriented position, as would be the case if the spring pressure remained on the connection.

Upon the rotation of the drill stem 10, it will be manifest that a rotation is imparted through the pins 25, 28 and 29 to the socket element 22. Since this element is directly connected to the bit body 15, said bit is rotated, as is the pilot bit 12 which is connected to the bit 15 through the pipe 17. During such rotation of the drill stem and also of the two bits, the pins 28 and 29 will reciprocate vertically within their respective slots 26 and 27 but at no time during such rotation will said pins engage the bottom of said recesses. The reciprocation of the pins within their slots is due to the knuckle joint connection, there being a relative sliding movement between the socket and collar 32 during rotation; the friction between the socket and collar is, of course, reduced to a minimum by the bearings 35. During the rotation of the bits 15 and 12, a suitable drilling mud may be circulated downwardly through the drill stem. This mud will pass downwardly through the bore 20a of the tubular shank 20, which bore extends completely through the ball element 19 and the depending pin 30. The circulating drilling fluid will then flow downwardly through the tubular pipe 17 and then outwardly through the port 12a in the pilot bit 12. A portion of this drilling fluid will also pass outwardly through the inclined ports or passages 18 in the bit body 15, whereby when the blades 14 of this

bit engage the formation, said blades are lubricated and the cuttings washed upwardly. It is pointed out that the drilling fluid which is flowing downwardly through the bit body 15 may also pass upwardly through the inclined passages 18 so that pressure of such fluid is directed against the annular packing ring 38 which packs off between the engaging surfaces of the ball 19 and its seat 37. Thus, the pressure of the drilling fluid is utilized to maintain a seal at this point so as to prevent the drilling fluid from contacting or entering the socket element 22. The spring 33 is disposed above the socket 22 and during the rotation of the tool, said spring is not acting downwardly to maintain the deflection of the bit. This is true because the pins 28 and 29 are disposed above the bottom of their respective recesses and the deflection of the tool is maintained by the engagement of the pilot bit 12 with the formation, together with the weight of the drill pipe or stem on said bit. With this arrangement, the pins are not subjected to a hammering action against the lower ends of the recesses and, therefore, excessive wear on the pins, as well as on their associate parts, is eliminated.

It is particularly noted that the pins 28 and 29 are employed primarily for the purpose of controlling the degree of deflection. However, they aid the pins 25 in setting up a rotatable connection between the ball and socket. At the time that the bits are rotating, there is no weight imposed on any of these connecting pins and they merely serve to impart rotation from the ball element 19 to the socket and then to the bit.

After the pilot bit has drilled through the formation a sufficient distance to move the main bit or reamer 15 to the bottom of the bore A, it will be obvious that this latter bit or reamer will engage the formation to drill a full gage hole. Thus, the well bore A may be continued at the same diameter in any desired direction as controlled by the deflection of the tool. It is noted that the bit blades 14 may be of such size as to drill a full gage hole because they are located substantially at the knuckle joint K, with the result that they do not have to undergo any substantial lateral movement upon the deflection of the tool.

The foregoing description of the invention is explanatory thereof and various changes in the size, shape and materials as well as in the details of the illustrated construction may be made, within the scope of the appended claims, without departing from the spirit of the invention.

What I claim and desire to secure by Letters Patent is:

1. A well bore deflecting tool including, a drill bit, means including a knuckle joint for operatively connecting said bit to the lower end of a drill string, a resilient means interposed between the knuckle joint and the drill string for yieldably directing said bit in a predetermined deflected direction relative to the drill string, and means for relieving the elements of the knuckle joint from the pressure of the resilient means when the bit is engaged with the formation to perform a drilling operation.

2. A well bore deflecting tool including, a drill bit, a reamer above the drill bit and connected thereto, a knuckle joint operatively connecting the reamer to a drill stem whereby the reamer and bit may be rotated about their own axis while positioned at an angle to the drill stem, means associated with the knuckle joint for yieldingly deflecting said bit and reamer at an angle with

respect to the drill stem, means incorporated within the knuckle joint for limiting the deflection of said reamer and bit, and means for relieving the knuckle joint of the pressure of the yieldable means when the bit engages the formation during the drilling operation.

3. A well bore deflecting tool including, a drill bit, a knuckle joint for operatively connecting the bit with a drill pipe whereby said bit may be rotated about its axis while positioned at an angle with respect to the drill pipe, yieldable means interposed between the knuckle joint and drill pipe and acting on said joint to normally yieldingly deflect said bit at an angle relative to the pipe, and means for relieving the elements of the knuckle joint from the pressure of said yieldable means upon relative longitudinal movement of the drill stem and bit.

4. A well bore deflecting tool including, a drill bit, a socket element connected to the upper end of said bit, a ball element connected to a drill stem and insertable within said socket element, whereby a knuckle joint connection between the bit and stem is provided, said ball having a loose fit within the socket so as to be capable of a limited vertical movement therein, coacting recesses and pins on the ball and socket elements for controlling the relative movement of the elements to each other and for rotatably connecting the elements, and a spring above the socket urging said socket downwardly on the ball so as to normally maintain the pins at the bottom of the recesses, whereby the drill bit is normally suspended from the drill stem at a predetermined angle of deflection.

5. A well bore deflecting tool including, a drill bit, a socket element connected to the upper end of said bit, a ball element connected to a drill stem and insertable within said socket element, whereby a knuckle joint connection between the bit and stem is provided, said ball having a loose fit within the socket so as to be capable of a limited vertical movement therein, coacting recesses and pins on the ball and socket elements for controlling the relative movement of the elements to each other and for rotatably connecting the elements, and a spring above the socket urging said socket downwardly on the ball so as to normally maintain the pins at the bottom of the recesses, whereby the drill bit is normally suspended from the drill stem at a predetermined angle of deflection, the recesses and pins being so located that when the drill bit is suspended during lowering, the ball is unseated within the socket and the weight of the bit is carried by the socket, downward movement of the ball element relative to the socket when further downward movement of the socket is prevented because of the bit striking the bottom of the bore, causing the ball to be seated, whereby the pins are moved upwardly in the recesses and the weight of the drill stem is carried solely by the engaging surfaces of the ball and socket during the rotating operation.

6. A well bore deflecting tool includin, a drill bit, a socket element connected to the upper end of said bit, a ball element connected to a drill stem and insertable within said socket element, whereby a knuckle joint connection between the bit and stem is provided, said ball having a loose fit within the socket so as to be capable of a limited vertical movement therein, coacting recesses and pins on the ball and socket elements for controlling the relative movement of the elements to each other and for rotatably connecting

the elements, and a spring above the socket urging said socket downwardly on the ball so as to normally maintain the pins at the bottom of the recesses, whereby the drill bit is normally suspended from the drill stem at a predetermined angle of deflection, the recesses and pins being so located that when the drill bit is suspended during lowering, the ball is unseated within the socket and the weight of the bit is carried by the socket, downward movement of the ball element relative to the socket when further downward movement of the socket is prevented because of the bit striking the bottom of the bore, causing the ball to be seated, whereby the pins are moved upwardly in the recesses and the weight of the drill stem is carried solely by the engaging surfaces of the ball and socket during the rotating operation, such downward movement of the ball within its socket also compressing the spring and relieving the pins of the pressure of such spring, whereby during the rotation of the stem and bit the pins function solely as a connection to impart rotation from the ball to the socket.

7. A well bore deflecting tool including, a drill bit, a socket element connected to the upper end of said bit, a ball element connected to a drill stem and insertable within said socket element, whereby a knuckle joint connection between the bit and stem is provided, said ball having a loose fit within the socket so as to be capable of a limited vertical movement therein, coacting recesses and pins on the ball and socket elements for controlling the relative movement of the elements to each other and for rotatably connecting the elements, and a spring above the socket urging said socket downwardly on the ball so as to normally maintain the pins at the bottom of the recesses, whereby the drill bit is normally suspended from the drill stem at a predetermined angle of deflection, the ball element having an unrestricted flow passage extending entirely therethrough, whereby a free circulation of drilling downwardly through the stem and ball and to the drill bit may be had.

8. A well bore deflecting tool including, a drill bit, a socket element connected to the upper end of said bit, a ball element connected to a drill stem and insertable within said socket element, whereby a knuckle joint connection between the bit and stem is provided, means on the socket and ball elements for limiting the relative movement of the socket and ball, whereby the angle of deflection of the bit relative to the stem is controlled, and a depending member on the ball element and movable within the bore of the bit to which the socket is connected for further controlling the relative movement between the ball and socket.

9. A well bore deflecting tool including, a drill bit, a socket element connected to the upper end of said bit, a ball element connected to a drill stem and insertable within said socket element, whereby a knuckle joint connection between the bit and stem is provided, said ball having a loose fit within the socket so as to be capable of a limited vertical movement therein, coacting recesses and pins on the ball and socket elements for controlling the relative movement of the elements to each other and for rotatably connecting the elements, a spring above the socket urging said socket downwardly on the ball so as to normally maintain the pins at the bottom of the recesses, whereby the drill bit is normally suspended from the drill stem at a predetermined

angle of deflection, and a depending member on the ball element and movable within the bore of the bit to which the socket is connected for further controlling the relative movement between the ball and socket.

10. A well bore deflecting tool including, a drill bit, a socket element connected to the upper end of said bit, a ball element connected to a drill stem and insertable within said socket element, whereby a knuckle joint connection between the bit and stem is provided, said ball having a loose fit within the socket so as to be capable of a limited vertical movement therein, coacting recesses and pins on the ball and socket elements for controlling the relative movement of the elements to each other and for rotatably connecting the elements, a spring above the socket urging said socket downwardly on the ball so as to normally maintain the pins at the bottom of the recesses, whereby the drill bit is normally suspended from the drill stem at a predetermined angle of deflection, the recesses and pins being so located that when the drill bit is suspended during lowering, the ball is unseated within the socket, and the weight of the bit is carried by said socket, downward movement of the ball element relative to the socket when further downward movement of the socket is prevented because of the bit striking the bottom of the bore, causing the ball to be seated, whereby the pins are moved upwardly in the recesses and the weight of the drill stem is carried solely by the engaging surfaces of the ball and socket during the rotating operation, the ball element having an unrestricted flow passage extending entirely therethrough, whereby a free circulation of drilling fluid downwardly through the stem and ball and to the drill bit may be had.

11. A well bore deflecting tool including, a drill bit, a socket element connected to the upper end of said bit, a ball element connected to a drill stem and insertable within said socket element, whereby a knuckle joint connection between the bit and stem is provided, said ball having a loose fit within the socket so as to be

capable of a limited vertical movement therein, coacting recesses and pins on the ball and socket elements for controlling the relative movement of the elements to each other and for rotatably connecting the elements, a spring above the socket urging said socket downwardly on the ball so as to normally maintain the pins at the bottom of the recesses, whereby the drill bit is normally suspended from the drill stem at a predetermined angle of deflection, the recesses and pins being so located that when the drill bit is suspended during lowering, the ball is unseated within the socket, whereby the weight of the bit is carried by said socket engaging the top of the ball, downward movement of the ball element relative to the socket when further downward movement of the socket is prevented because of the bit striking the bottom of the bore, causing the ball to be seated, whereby the pins are moved upwardly in the recesses and the weight of the drill stem is carried solely by the engaging surfaces of the ball and socket during the rotating operation, the ball element having an unrestricted flow passage extending entirely therethrough, whereby a free circulation of drilling fluid downwardly through the stem and ball and to the drill bit may be had, means for packing off the engaging surfaces of the ball and socket when said ball is seated, and means for circulating a drilling fluid downwardly through the ball element and to the bit during rotation of said bit.

12. A well bore deflecting tool including, a drill bit, a socket element connected to the upper end of said bit, a ball element connected to a drill stem and insertable within said socket element, whereby a knuckle joint connection between the bit and stem is provided, means for rotatably connecting the ball and socket elements and arranged so as to permit a deflection of the socket on the ball, and depending means on said ball coacting with the bore of the socket for limiting the deflection of said socket and for relieving the connecting means of shearing stresses.

WILLIAM N. OSWALD.
